(57) **CLAIM**

The ornamental design for the LED array for illumination of signs as shown.

DESCRIPTION

FIG. 1 is a front elevation view of the LED array for illumination of signs shown in an environment of use.

FIG. 2 is a front elevation view of the LED array for illumination of signs.

FIG. 3 is a rear view thereof.

FIG. 4 is a top plan view thereof.

FIG. 5 is a bottom plan view thereof.

FIG. 6 is a right side elevation view thereof, the left side elevation view being a mirror image;

FIG. 7 is a front elevation detail view of the corner portion indicated by arrow 7 of FIG. 2, showing an LED element which is positioned in repeating pattern, as seen in FIGS. 2-6, and shown separately for clarity of illustration.

FIG. 8 is a rear detail view thereof.

FIG. 9 is a top plan detail view thereof.

FIG. 10 is a bottom plan detail view thereof; and,

FIG. 11 is a right side detail view thereof, the left side detail view being a mirror image; and,

FIG. 12 is an isometric detail view thereof.

The broken dash lines in the figures are for illustrative purposes only and represent non-claimed environmental structure. Neither the portions of the environmental structure shown in broken dash line nor the broken dash lines themselves form any part of the claimed invention.

The broken dash-dot lines in the figures depict portions of the article that form no part of the claimed design. Neither the portions of the article shown in broken dash-dot line nor the broken dash-dot lines themselves form any part of the claimed invention.
